UNITED STATES PATENT OFFICE.

GUSTAVE E. VILLARET, OF LEONIA, NEW JERSEY, ASSIGNOR TO MARKEL ELECTRIC PRODUCTS, INC., OF BUFFALO, NEW YORK, A CORPORATION OF NEW YORK.

DESIGN FOR A TABLE STANDARD.

Application filed November 23, 1928. Serial No. 29,006. Term of patent 3½ years.

To all whom it may concern:

Be it known that I, GUSTAVE E. VILLARET, a citizen of the United States, residing at Leonia, in the county of Bergen and State of New Jersey, have invented a new, original, and ornamental Design for Table Standard, of which the following is a specification, reference being had to the accompanying drawing, forming part thereof.

In said drawing:

Figure 1 is a side elevation of a table standard embodying my new design. In this figure

half of the design is shown in full lines while the remaining half is shown in outline in dot and dash lines, the pattern being repeated. It will be understood that the column shown in this figure is of general oval shape.

Figure 2 is a top plan view of the same, similarly executed in full and dot and dash lines.

I claim:

The ornamental design for a table standard, substantially as shown and described.

GUSTAVE E. VILLARET.
